RAILWAY JOURNAL LUBRICATOR

James J. Hennessy, Montclair, N. J.

Application March 11, 1944, Serial No. 526,003

9 Claims. (Cl. 308—84)

1

The invention relates to railway journal lubricators of the type in which a pump is utilized to raise lubricant from the bottom of a journal box or other sump to a distributor applied to the journal to be lubricated. Such a pump is shown in Patent No. 2,331,835, issued to the present applicant October 12, 1943.

The present invention relates particularly to the means incorporated in such an arrangement for leading oil from the pump to the journal or to the distributor by which lubricant is applied to the face of the journal, as distinguished from hinged arm distributors of the type shown in said patent and telescoping or hose connections as shown, for example, in Patent No. 2,162,383, issued to the present applicant June 13, 1936.

The main object of the present invention is to simplify the involved structure.

Another object of the invention is to provide a distributor structure, including an extensive conduit, which may be completed and handled and inserted into and removed from the journal box separately from the pump.

These and other detail objects as will appear from the following description are attained by the structure illustrated in the accompanying drawings, in which—

Figure 1 is a longitudinal vertical section through a journal box equipped with a pump type lubricator.

Figure 2 is a vertical transverse section taken on the line 2—2 of Figure 1.

Figure 3 is a detail section drawn to an enlarged scale and corresponding to a portion of the structure shown in Figure 2.

Figure 4 is a section corresponding generally to Figure 3 but illustrating another form of the invention.

The journal box 1 is a typical A. A. R. box arranged for application to the usual axle journal 2. The pump includes a body 3 and one or more operating levers 4 arranged to be actuated by the movement of the journal axially in the box. The pump is positioned in the box by a plate 5. The oscillation of pump lever 4 causes lubricant to be drawn into the lower portion of the pump and discharge through an outlet 6. Preferably outlet 6 opens into the bottom of a cup-shaped depression in the top of the pump body. A member 7 comprising a spring seat has a ball-shaped nipple fitting in the depression in the top of the pump. Member 7 is apertured in line with outlet 6.

A distributor device is applied to the journal to be lubricated and preferably comprises an

2

arcuate plate 8 with upstanding ribs and ridges 9 forming a pan-like device for holding lubricant against the journal. Plate 8 is supported by slabs 10 of felt or similar material which, in turn, are carried upon supports 11 hinged to a center piece 12. This arrangement may correspond to that shown in a copending application, Serial No. 472,189, filed January 13, 1943, by the present applicant (now Patent No. 2,378,407, issued June 19, 1945). A coil spring 13 is compressed between seat 7 and center piece 12 and yieldingly supports the latter and the remaining portions of the distributor so as to thrust the upper face of the distributor against the journal.

Distributor or plate 8 has a through passage for lubricant, including an inlet 14 which is spaced above discharge outlet 6 in the pump body.

A bellows-type tube 15 is employed as a conduit between the pump and distributor and consists of a length of tubular material with its wall bent alternately inwardly and outwardly, as best shown in Figure 3. The material may be of flexible brass or other metal alloy or of suitable fabric or synthetic rubber which is resistant to destructive action by oil, etc.

The upper end of tube 15 is cemented or otherwise secured to a flat plate 16 which lies against a suitable flat surface provided on the bottom of plate 8. The lower end of tube 15 is similarly secured to a flat plate 17 which lies against the upper surface of seat 7. Plates 16 and 17 are apertured to cooperate with the passage 19 in seat 7 and with inlet 14 in plate 8. A helical spring 20 surrounds tube 15 and is compressed between plates 16 and 17 to thrust them in opposite directions and hold them to their seats on the associated parts 7 and 8.

Preferably two or more links 21 are pivotally secured to plate 8 and depend therefrom and are freely received in openings in member 7 and are provided with cotters 22 at their lower ends. These pins guide members 7 and limit the spring thrust movement of members 7 and 8 away from each other if they are disassembled from the pump and journal. Hence the distributor unit, including seat member 7, may be handled separately and may be readily inserted and removed from the journal and box.

Figure 4 illustrates another arrangement in which the bellows tube 25 is formed by a leather sleeve shaped and stitched as illustrated with its ends flanged as shown at 26 and gripped between plates 27 and 28 which may be welded together as indicated at 29. A spring 30 compressed be-

tween the upper and lower plates 27 tends to expand the tube lengthwise to maintain contact of upper and lower plates 28 with the distributor and pump parts with which they are associated.

The details of the structure may be varied substantially without departing from the spirit of the invention, and the exclusive use of those modifications coming within the scope of the claims is contemplated.

What is claimed is:

1. In a journal lubricator of the class described including a pump and a distributor above the same for application to the journal to be lubricated, and a conduit comprising a bellows leading in a substantially straight line from the pump to the distributor and constructed to automatically shorten and lengthen along said line to accommodate variations in the distance between the pump and distributor.

2. In a journal lubricator of the class described including a pump and a distributor above the same for application to the journal to be lubricated, a conduit between said pump and distributor embodying a tube with walls of flexible material folded alternately inwardly and outwardly to form a cylindrical bellows open at its ends to the pump and distributor respectively and extending in a substantially straight line between the pump and distributor and flexing lengthwise of said line to readily accommodate movement of the pump and the distributor relative to each other.

3. In a journal lubricator, a pump, a distributor, a conduit between said pump and distributor comprising a bellows-like tube and a plate secured to each end of the tube and apertured for the passage of lubricant therethrough, and a spring compressed between said plates and thrusting them apart towards the pump and distributor respectively.

4. In a journal lubricator, a distributor arranged for application to the underside of a journal and provided with a through passage for leading lubricant to the journal-opposing surface of the distributor, a lubricant pump arranged for application to the bottom of a journal box and having a lubricant outlet, a member resting on said pump and having an aperture in line with said outlet, a spring compressed between said member and distributor, and a bellows-like tube extending between said member and distributor and forming a conduit between said aperture and said passage.

5. In a journal lubricator, a distributor having a port arranged for application to the underside of a journal and provided with a through passage with an inlet for leading lubricant to the journal-opposing surface of said port, a member underlying said distributor and apertured in line with the inlet to said passage, a pump arranged for application to the bottom of a journal box and having a lubricant outlet, a member overlying said pump and apertured in line with said outlet, a bellows-like tube secured at its opposite ends to said members and forming a conduit between said outlet and inlet, and a helical spring surrounding said tube and compressed between said members to thrust them against the distributor and pump respectively.

6. In a journal lubricator, a pump arranged for

application to the bottom of a journal box and having an upwardly opening lubricant outlet, a member overlying the pump and having a passageway aligned with said outlet, a spring carried upon said member, a distributor supported by said spring and arranged for application to the bottom of a journal in the journal box, elements depending from said distributor and slidably received in said member and provided with means

5 10 limiting the relative movement of said distributor and member away from each other, and a flexible tube between said member and distributor forming a conduit from the pump outlet to the distributor inlet.

15 7. In a journal lubricator, a distributor arranged for application to the underside of a journal and provided with a downwardly facing flat face provided with an inlet opening, a pump arranged for application to the bottom of a journal

20 box and having an upwardly facing concavity provided with a central outlet opening, a member having a downwardly facing convex boss seated in said concavity and apertured in line with said outlet opening, a plate on said member

25 and similarly apertured, a spring seated on said plate, a top plate supported by said spring against said flat bottom face on the distributor, and a bellows-like tube with its opposite ends connected to said plates respectively and surrounding said openings and forming a conduit between said pump and distributor.

30 8. A structure as described in claim 7 which includes pins spaced transversely of said openings and tube and secured to the distributor and slidable through the spring-supporting plate, and means on said pins limiting the supporting plate against movement away from the distributor to hold them assembled when separated from the pump.

35 40 9. In a journal lubricator, a pump, a lubricant distributor above the same, a conduit between the pump and distributor comprising a bellows-like tube with its ends flanged outwardly, an annular plate surrounding the tube inwardly of each flanged end, and a plate overlying each of said flanged ends and apertured for the passage of fluid to and from the tube and fitting against the pump and distributor respectively, the plates at each end of the tube being secured together to clamp the flange of the tube between them, and a spring compressed between the annular plates and thrusting them apart to extend the tube.

JAS. J. HENNESSY.
